UNITED STATES PATENT OFFICE.

PETER H. JACKSON, OF SAN FRANCISCO, CALIFORNIA.

ILLUMINATING BASEMENTS.

SPECIFICATION forming part of Letters Patent No. 314,026, dated March 17, 1885.

Application filed July 21, 1884. (No model.)

To all whom it may concern:

Be it known that I, PETER H. JACKSON, of the city and county of San Francisco, and State of California, have invented an Improvement 5 in Illuminating Basements; and I hereby declare the following to be a full, clear, and exact description thereof.

My invention relates to certain improvements in the illumination of basements of 10 buildings by means of glazed tiles.

It consists of tiles made in patterns of such a description that they can be kept in any quantity and in stock and ready for use upon any building without regard to the regularities 15 of outline in the contour of the building-front, and in connection with these of similar plates, which may be either plain or glazed, which will be fitted to the outline or contour of the building where the tiles are to be used. 20 Together with this I employ certain means for supporting the different parts, joining them to each other, and forming joints between them which will not leak, all of which will be more fully explained by reference to the accompanying drawings, in which—

Figure 1 is a plan view showing the irregular outline of the building-front and the manner of applying tiles. Figs. 2 to 11, inclusive, are vertical sections taken through a tile, showing the bottom of the column, the riser, and means for supporting the outer and inner ends 30 of the tiles and the bearers.

It is usual where a new building is to be constructed, and illuminating-tiles or iron-work is to be fitted to the pavement or sidewalk in front of the building, to wait until the columns, sills, and risers are placed in position before the tiles are constructed, in order to make good joints and a close fit between parts. 35 This is necessary, because these parts of the iron-work rarely come into the exact place which is designated by the drawings, owing to the slight change in the form in casting the metal, or from other reasons. The tiles are 40 then fitted to the irregularities of the contour of the front of the building, and are then glazed and placed in position.

My invention contemplates the construction 45 of tiles of a certain length, made preferably of rectangular form, so that they can be laid in front of the building without regard to the contour, and with these of supplemental irregu-

lar plates or tiles, one edge of which will be fitted against those already described, while the other may be fitted to the contour of the 55 building.

It also consists in a means for supporting these sections and connecting them so as to make water-tight joints.

A is a building, the front having columns 60 B B, riser C, and sills, in the usual manner.

The tiles D are made of any suitable or desired form, but preferably rectangular in shape, and made to fit the outer edge of the contour tiles or plates, and of an equal size, 65 with means for securing them in place, so that in whatever building they may be employed they can be laid without reference to the particular contour of the building. These tiles have their inner edges supported within a cer- 70 tain distance of the building, and the space between is then filled in with tiles or plates E, which are formed to fit the irregularities of the front. By this construction I am enabled to carry any desired quantity of tiles in 75 stock ready to be laid, and the only portion which it is necessary to fit to the particular building in consideration will be the sections E, and this can be done at a small expense and 80 in a short time.

In order to secure these tiles and pieces, various means may be used. In the figures from 2 to 8 I have shown several methods.

In Fig. 2 the riser has a flange, F, projecting outward from its lower edge, and the inner 85 edge of the separate pieces E may rest upon it, while the outer edges of these pieces have vertical and outward-projecting horizontal flanges G, upon which the tiles D may rest, and to which they may bolted.

In Fig. 3 I have shown the riser and the filling-in piece cast in one with the same flange 90 for supporting tile D.

In Fig. 4 I have shown a small beam, H, upon which the inner edge of the tiles D and 95 the outer edge of the plates E may rest and be secured. The meeting edges of the tiles D are supported upon bearers I, which extend inward to the supporting-flange and from them outward to the wall, vault-beam, or girder, 100 forming an end support or flange, upon which the tile rests. The bearers are constructed with deep strengthening-ribs, as shown in my patent of August 29, 1883, and these ribs ex-

tend the full length of the tile and are recessed on the top to receive a cross-bearer, K, extending over and resting on the top of the next bearer and bolted to them, and the meeting edges of the tiles D and E rest upon this cross-bearer and are bolted to it, and cement is run in or pressed in between the tiles and all is made water-tight.

Fig. 7 shows the recessed longitudinal bearer I and the meeting edges of the tiles D and E, one end of which has a flange cast upon it and receives the end of the other on the top of the flange, and is bolted to it in the manner described.

In many cases these tiles must be laid so as to conform to the grade of the street, which may have considerable inclination along the front of the building. In order to support these tiles upon the proper grade, the bearers are so laid as to conform to this grade, the ends *i*, where they rest on the end supports, being of such different heights that the tiles will take the proper grade when they are laid upon them. In order to support the tiles at points between the bearers, either at the middle, or, if they are wide, at more than one point, I employ wedges or blocks J, of iron or other unyielding material, which are placed between the ends of the tiles and the surface upon which the bearers rest, thus preventing the tile from bending between the bearers and its end supports after the bearers, blocks, or wedges are adjusted, so that the surface is at the right grade. Either fusible cement is run in or plastic cement filled and pressed into the crevice, filling up the entire space between the end of the tile and its end bearings and surrounding ends of the bearers as well as blocks or wedges, so that they are united in a solid body, unyielding and water-tight, with very little expense. If these tiles are simply laid upon the bearers with their ends resting on brick-work, as shown in Figs. 10 and 11, without being secured, they might be lifted by the use of a bar or other device, as there is no means of fastening at the crown of the arch, so that burglars could obtain easy entrance into basements. In order to prevent this and secure the tiles firmly at their outer ends, I employ channel or other bars of iron, which extend along the outer edge of the illuminating-tile over the end supports, usually having a width of about two inches. These iron bars are secured to the beams by bolts or otherwise, and the outer ends of the tiles are then secured to these bars, by which means it will be impossible to raise or move them from their position. At points between the bearers these channel-iron bars may have bolts passing through the blocking bases before described and into the vault-beams below. The whole is then firmly secured, the channel-iron bars being supported at intervals between the bearers and prevented from bending.

I do not claim, broadly, a sectional exten-

sion of the area or vault cover composed of sectional tiles inserted in or supported by a metal frame bolted to it, as described in the Reissue Patent No. 9,883 of T. Hyatt; neither do I claim an extension area or vault cover composed of sectional illuminating-tiles, each alternate tile having cast at one or both edges strengthening-ribs projecting laterally to form a seat for the next tile to rest on.

Having thus described my invention, what I claim as new, and desire to secure by Letters Patent, is—

1. Tiles covering areas and made in two sections in the direction of their length, said tiles being joined together at their meeting edges on the same plane, without intervening risers, the outer sections being rectangular in shape, and the inner ones having their inner edge made to fit the contour of the building-front, and without surrounding metal frames, together with supporting-flanges F G or beams H, as herein described.

2. Tiles covering areas and made in two sections, the outer one of which is rectangular in form and the inner one fitted to its inner edge, while its own inner edge is made to fit the contour of the building, said tiles being made without surrounding metal frames, and having supporting-flanges between the two and extending their entire length, together with bearers having strengthening-ribs and shoulders upon which the sections are supported, substantially as described.

3. Tiles covering areas and made in two sections fitted to each other and the building contour, as shown, having connecting-flanges between the two, together with bearings having deep strengthening-ribs and shoulders extending the entire length of both tiles, so as to rest upon the end supports, substantially as herein described.

4. Tiles covering areas and resting on strengthening-bearers extending longitudinally with both tiles, and having end supports, said bearers being made of different depths where they rest upon their end supports, so that the tiles may conform to the grade of the street, substantially as herein described.

5. Tiles made in sections covering areas, and resting on bearers which extend longitudinally with both tiles, and resting on the end supports, in combination with blocks or wedge-pieces on the end supports and between the bearers, and a filling of fusible or plastic cement about the blocks or wedges in the ends of the bearers, substantially as herein described.

6. Tiles made in sections covering areas and resting on strengthening-ribs which extend longitudinally with the tiles, in combination with iron bars extending along the outer edges of the tiles, which are secured to them, said bars being secured to the beam or girder, substantially as herein described.

7. Tiles made in sections and covering areas, as shown, said tiles resting on strengthening-ribs or bearers extending longitudinally with the tiles and resting upon end supports, in combination with channel-iron or other bars extending beneath the outer edges of the tiles, which are bolted to a support by them, and a fusible or plastic cement filling at the outer

ends of the tiles and bars, substantially as herein described.

In witness whereof I have hereunto set my hand.

PETER H. JACKSON.
